CLAIM

The ornamental design for a spout, as shown and described.

DESCRIPTION

In a preferred embodiment, the nature of this product is as a plumbing fixture in the form of a spout primary useful for washing various items and/or body parts such as in a bath tub.

FIG. 1 is a right, top, front perspective view of a spout embodying our new design;

FIG. 2 is a right side elevational view thereof, the left side elevational view thereof being a mirror image of the right side shown;

FIG. 3 is a top plan view thereof;

FIG. 4 is a front elevational view thereof;

FIG. 5 is a bottom plan view thereof; and,

FIG. 6 is a rear elevational view thereof.

The broken line representations of pull-up knob environment in FIGS. 1-4 and 6 and of openings in FIGS. 5 and 6, are for the purpose of illustration only, and form no part of the claimed design.
